Attorney

UNITED STATES PATENT OFFICE.

GEORGE TRUMPETER, OF ALLIANCE, OHIO.

ICE PICK.

1,424,221.

Specification of Letters Patent. Patented Aug. 1, 1922.

Application filed March 8, 1922. Serial No. 542,041.

To all whom it may concern:

Be it known that I, GEORGE TRUMPETER, a citizen of the United States of America, residing at Alliance, in the county of Stark 5 and State of Ohio, have invented certain new and useful Improvements in Ice Picks, of which the following is a specification.

This invention relates to certain new and useful improvements in ice picks and has 10 particular reference to the provision of a resiliently mounted pick point or blade carried by a handle.

The primary object of the invention resides in the provision of an ice pick wherein 15 a handle provided with an elongated socket resiliently houses a pick point capable of being locked to the handle in a rigid condition, in either a projected or retracted position.

20 The invention further provides in an ice pick of the type above set forth the idea of completely housing the pick point when out of use to prevent injury or damage to adjacent objects.

25 With these general objects in view and others that will appear as the nature of the invention is better understood, the same consists in the novel construction, combination, and arrangement of parts hereinafter more 30 fully described, illustrated in the accompanying drawing, and pointed out in the appended claims.

In the drawing forming a part of this application, and in which like designating 35 characters refer to corresponding parts throughout the several views,

Figure 1 is a side elevational view of an ice pick constructed in accordance with the present invention, with the pick point in 40 its retracted housed position,

Figure 2 is a longitudinal sectional view showing the resiliently mounted pick point in a rigid position slightly projected from the end of the handle device, for purposes 45 of marking or scoring a block of ice, and showing the pick point by dotted lines in its extended position,

Figure 3 is a cross sectional view taken on line III-III of Figure 2, showing the 50 pick point locked to a part of the handle,

Figure 4 is a side elevational view of the tubular member removed from the handle,

Figure 5 is a side elevational view of the

lock nut for holding the pick point in its retracted housed position, 55

Figure 6 is a top plan view of the lock nut,

Figure 7 is a side elevational view of a screw plug forming an abutment for one end of a spring, 60

Figure 8 is a side elevational view of the pick point,

Figure 9 is a side elevational view of the larger spring positioned between the head of the pick point and the upper end of the 65 tubular member,

Figure 10 is a side elevational view of the smaller spring surrounding the pick point, and

Figure 11 is a side elevational view, partly 70 in section, of the tensioned sleeve, enclosing the pick point.

The ice pick disclosed in this application embodies a handle 1 provided with an elongated end opening socket 2 within which 75 the tubular member 3 is disposed. The specific construction of the tubular member 3 shown more clearly in Figs. 2 and 4 is longitudinally and diametrically slotted as at 4, to provide two substantially semi-circular side sections, as shown in Figure 3, that carry at adjacent ends an integral annular collar 5 threaded over a portion of the length thereof as at 6. The edges of the slotted opening 4 are provided with side 80 notches 7, while similar notches 8 are formed in the side walls of said slots adjacent the threaded portion 6 of the thimble.

A sleeve member 9 open at each end, is internally threaded at one end as at 10 and 90 carries outwardly directed, diametrically opposite lugs 11 at the other end thereof, the sleeve 9 being inserted into the tubular member 3 with the lugs 11 sliding in the side slots 4 of the tubular member, the lugs 95 11 engaging the thimble 5 to prevent complete passage of the sleeve through the tubular member.

The pick shown in Figure 8 embodies an elongated shank stem 12 provided upon 100 one end with a point 13, and carries at the opposite end thereof, a disk head 14, provided with diametrically opposite outwardly projecting lugs 15. A coil spring 16, such as shown in Figure 10, surrounds the 105 shank stem 12, of the pick, and the pick and

spring 16 are inserted in the tubular member 3 with the side lugs 15 of the pick head sliding in the side slots 4 of the tubular member.

5 The threaded end of the sleeve 9 projects from the thimble end of the tubular member and has freely mounted thereon the lock nut 17, the upper edge of which carries opposite notches 18, the lock nut 17 sliding over the 10 collar 5, for engagement with the threads 6 of the thimble for purposes presently to appear. The coil spring 16, surrounding the shank stem of the pick engages at one end, the pick head 14, while the other end 15 of the spring is engaged by a tubular screw plug 19 shown in Figures 2 and 7, that is threaded into the internally threaded end 10 of the sleeve with the pick point 13 freely projecting through the tubular screw plug, 20 said plug carrying upon the outer end thereof 25 an outwardly directed annular flange 20. A coil spring 21, as shown in Figure 9, is then inserted in the upper end of the tubular member 3 and engages at its lower end, 30 the disk head 14 of the pick point, the spring being confined within the tubular member by the plug 22 inserted in the outer end thereof. The tubular member 3 resiliently supporting the pick point is then positioned in the socket 2, formed in the handle 1, and the cross pin 23 carried by the handle and passing through the side sections of the tubular member and the plug 22 anchors 35 the pick mechanism to said handle, as shown clearly in Figure 2.

From the above detailed description of the device, it is believed that the construction and operation thereof will at once be apparent, it being noted that in normal position, 40 the pick point 13 is retracted into the sleeve 9 to be housed therein, or in other words, the spring 16 engaging the head 14 of the pick and the tubular nut 19, forces the sleeve 9 at its limit of outward movement relative to the 45 handle for enclosing the pick point. Assuming that the lugs 11 carried by the sleeve 9 and the lugs 15 carried by the pick head 14, are aligned in the slot 4 of the tubular member, the tubular nut 19 turning the flange 20 50 is moved into engagement or impact with a block of ice, and upon such contact, the sleeve is moved inwardly of the tubular member and the pick point 13 allowed to project therefrom for breaking the ice, the pick being 55 tensioned by the relatively strong spring 21 as will be readily understood.

Should it be desired to cause the pick point 13 to be slightly projected from the outer end of the sleeve 9, said sleeve is moved 60 inwardly of the tubular member against the tension of the two springs and rotated relative thereto to position the lugs 11 in the side notches 7, thus holding the sleeve in a slightly retracted position with the pick 65 point projecting from the outer end thereof.

as shown by full lines in Fig. 2 for scoring or otherwise marking ice.

When it is desired to lock the pick point in a retracted housed position as shown in Figure 1, the tubular nut 17 is moved to engagement with the threaded portion 6 of the thimble 5 with the lugs 11 carried by the sleeve 9 received in the notches 18 of the nut 17, and continued movement of the nut will move the sleeve lugs 11 into the side notches 8 of the tubular member, thereby locking the sleeve in its extended position and against movement relative to the tubular member 3, so that the pick point will be prevented from projection outwardly of the sleeve. 75

It is also possible to lock the pick point in a rigid extended position as shown by dotted lines in Fig. 2, the pick point being moved outwardly of the sleeve 9 against the tension of the spring 16 to position the lugs 15 carried by the head 14 in the side notches 7. 80

It will be noted that applicant has provided an efficient type of ice pick wherein the pick point is resiliently mounted with respect to the handle carrying the same, and with the pick point capable of being rigidly connected to the handle in either retracted or extended position. 90

Minor changes in the details of construction are contemplated without departing from the spirit and scope of the invention as hereinafter claimed. 95

What I claim is:—

1. An ice pick of the type described comprising a socketed handle, a tubular member secured therein, a sleeve slidable in said tubular member and extending outwardly of said handle, a pick point slidable in said tubular member and sleeve, a cushioned spring interposed between the inner end of the pick point and handle, and a cushioned spring surrounding the pick point and engaging at its opposite ends, the inner end of the pick point and the outer end of the sleeve. 100

2. The construction called for by claim 1, characterized by cooperating means carried by the tubular member and sleeve for holding the sleeve immovable relative to the tubular member for completely housing the outer end of the pick point or rigidly holding the pick point slightly projected. 110

3. The construction called for by claim 1 characterized by cooperating means carried by the tubular member and pick point for rigidly holding the pick point in an extended 120 position.

4. An ice pick of the type described comprising a socketed handle, a tubular member anchored therein, said tubular member having longitudinal slots in the opposite walls thereof, with recesses formed in the walls of said slots, a thimble threaded over a portion of the length thereof, carried by one end of the tubular member, a sleeve slidably mounted in the tubular member, diametri- 125

cally opposite lugs carried by the sleeve, moving in the slots of the tubular member, and adapted to be received in said recesses, a pick point resiliently mounted in the tubular member and sleeve, a disk head carried by the pick point, diametrically opposite lugs carried by said disk head extending into the sleeve slots and adapted to be moved

into said recesses and a tubular nut threaded on the thimble and having notches on one edge thereof to receive the sleeve lugs to move said lugs into one of the recesses formed in the tubular member for holding the sleeve immovable relative to the tubular member.

In testimony whereof I affix my signature. 15

GEORGE TRUMPETER.
